ABSTRACT: A compensated flat directional coupler includes a main branch carrying an electrical signal and a coupled branch carrying a coupled electrical signal responsive to the signal on the main branch. The coupled branch includes an auxiliary compensating network in the output portion of the coupled branch. The auxiliary compensating network couples to the coupled branch and is substantially isolated from the main branch. The auxiliary compensating network is substantially independent of the coupling between the main and coupled branch. The auxiliary coupling network renders the ratio of coupled output signal to the main branch output signal substantially independent of input signal frequency variation.

COMPENSATED FLAT DIRECTIONAL COUPLER

BACKGROUND OF THE INVENTION

The present invention relates in general to directional couplers and more particularly concerns a novel compensated flat directional coupler of high electrical performance and small physical form which is relatively easy and inexpensive to fabricate in large and small quantities with uniformly high quality.

In the well-known type of directional couplers many cascaded coupling sections are used to achieve flat coupling. These cascaded sections interact with one another to produce the desired frequency response. While these directional couplers perform satisfactorily, the relatively large size, as is required by the many cascaded sections, usually renders the resulting structure extremely large and unwieldy. Moreover, the use of these multiple cascaded sections usually requires exacting construction to achieve the desired results. In addition, the use of these procedures tends to increase the cost of the resulting directional coupler.

Accordingly, it is an important object of the invention to provide a compensated flat directional coupler which is relatively easy and inexpensive to fabricate.

It is another object of the invention to provide compensated flat directional coupler in a compact, efficient package capable of reproduction in large or small quantities.

It is another object of the invention to provide a compensated flat directional coupler with a minimum of coupling sections having a compensating network in the coupled path.

It is another object of the invention to provide a compensated flat directional coupler having the ratio of coupled output signal to main branch output signal substantially independent of frequency variation of input signal.

Another object of the invention is to provide a compensated flat directional coupler having a compensating network in the coupled output branch where the characteristics of the compensating network are substantially independent of the coupling of the directional coupler.

Another object of the invention is to provide a compensated flat directional coupler having a compensating network in the coupled output branch whose characteristics are dependent virtually exclusively on the bandwidth desired.

It is another object of the invention to provide a compensated flat directional coupler with a compensating network in the coupled path which may be integrally combined in a single package with the main coupler or attached externally by suitable connecting apparatus.

It is another object of the invention to provide a compensated flat directional coupler operable over a broad band of frequencies which is susceptible to sealed or unsealed operation.

Another object of the invention is to achieve one or more of the preceding objects while keeping costs relatively low.

SUMMARY OF THE INVENTION

According to the invention, there is a directional coupler operative over a frequency range embracing a predetermined center frequency and a source supplying an input electrical signal. The directional coupler includes a main branch carrying an electrical signal responsive to the input signal and a coupled branch carrying a coupled signal responsive to the signal on the main branch. The output portion of the coupled branch includes an auxiliary compensating network coacting with the coupled branch and substantially isolated from the main branch. The auxiliary compensating network includes two identical cascaded coupling sections each coacting with the coupled branch for a length corresponding substantially to an odd multiple of quarter wavelengths at the center frequency of the directional coupler. The coupling sections are terminated in substantially nonreflecting terminations. The coupling values of the identical coupling sections are chosen so that the

auxiliary compensating network renders the ratio of the coupled output signal to the output signal from the main branch substantially independent of frequency variation of the input signal.

5 Numerous other features, objects and advantages of the present invention will be more clearly understood when considered in conjunction with the accompanying drawings in which:

BRIEF DESCRIPTION OF THE DRAWING

FIG. 1 is a block diagram illustrating the logical arrangement of the apparatus and the power flow through the invention, and;

15 FIG. 2 is a schematic circuit of an embodiment of FIG. 1 further showing the elements of the compensating network.

DETAILED DESCRIPTION OF THE PREFERRED EMBODIMENTS

20 With reference now to the drawings and more particularly to FIG. 1 thereof, there is shown a block diagram illustrating the logical arrangement of the apparatus and the power flow through the invention (the flow of power is represented by arrows in the figure). The directional coupler 20 operates over a frequency range embracing a predetermined center frequency. Power flows into directional coupler 20 from signal terminal 10 and continues through the coupler to the main line 21 and main line output terminal 12. Some portion of this input power (to be determined by coupling coefficient k_1 of the directional coupler 20) is coupled from the main branch 21 to the coupled branch 31. The direction of the flow of coupled power will be the reverse of the input flow, as is shown in FIG. 1. Thus, the coupled power impinges upon output terminal 16 of directional coupler 20. Compensating network 40 is serially connected with coupled branch 31. Network 40 is chosen so that the ratio of coupled power P_c at terminal 18 to the output power P_o at terminal 12, is essentially independent of the frequency variation of the input power P_{in} .

40 FIG. 2 is a schematic circuit diagram of an embodiment of FIG. 1 further illustrating the elements of compensating network 40 and of directional coupler 20. Main branch 21 is interposed between signal terminals 10 and 12. Coupled portion 33 of coupled branch 31 is separated from coupled portion 23 of main branch 21 for a length θ so as to achieve coupling of a degree characterized by coupling coefficient k_1 . The length θ corresponds to an odd multiple of quarter wavelengths at the predetermined center frequency of directional coupler 20. Coupled output terminal 16 of coupled branch 31 is serially connected to series conductor 39 of compensating network 40. Compensating network 40 includes auxiliary portions 34 and 36 each respectively separated from coupled portions 37 and 38 of series conductor 39 also θ so that a degree of coupling characterized by coupling coefficient k_2 is achieved. Auxiliary coupled line 34 is terminated in substantially reflectionless terminations 35 and 35A. Auxiliary coupled line 36 is terminated in substantially reflectionless terminations 35B and 35C. Signal terminal 18 defines the remaining terminal of conductor 39 and provides the output terminal for the invention. Terminal 14 may be connected to a substantially reflectionless termination 50 which may be integrally combined with the coupler.

Having described the embodiments and the physical arrangement of the circuit components, it is appropriate to consider the techniques and calculations used in the design. Referring again to the schematic circuit diagram of FIG. 2, the power, P_{in} , on terminal 10 may be arbitrarily assigned the value of unity. Using well-known single section directional coupler equations, it can be shown that:

$$P_o = \frac{1 - k_1^2}{1 - k_1^2 \cos^2 \theta} \quad (1)$$

where $\theta = (2\pi l/\lambda)$, and the single section directional coupler has the coupling coefficient of k_1 .

The coupled output power (at terminal 16) may then be represented by:

$$P'_c = \frac{k_1^2 \sin^2 \theta}{1 - k_1^2 \cos^2 \theta} \quad (2)$$

This value at terminal 16 forms the input for compensating network 40 which includes two coupled sections each having a coupling coefficient k_2 , so that:

$$P_o = \frac{k_1^2 \sin^2 \theta}{1 - k_1^2 \cos^2 \theta} \left(\frac{1 - k_2^2}{1 - k_2^2 \cos^2 \theta} \right)^2 \quad (3)$$

which is the coupled output power at terminal 18. For a flat directional coupler the value of P_o over P_c is desired to be constant. Thus, the frequency variable and midband coupling terms must be separated:

$$\frac{P_o}{P_c} = \frac{1 - k_1^2}{k_1^2 (1 - k_2^2)^2} \left(\frac{1 - k_2^2 \cos^2 \theta}{\sin \theta} \right)^2 \quad (4)$$

We may then define the midband coupling and frequency variable terms:

$$K = \frac{1 - k_1^2}{k_1^2 (1 - k_2^2)^2} \quad (5)$$

and

$$\beta = \frac{1 - k_2^2 \cos^2 \theta}{\sin \theta} \quad (6)$$

therefore:

$$(P_o/P_c = K\beta^2) \quad (7)$$

This frequency variable term β is a function only of θ and the coupling coefficient of the auxiliary network k_2 .

The maximum value of the frequency dependent term may be calculated using differential calculus techniques, so that:

$$\sin^2 \theta = \frac{1 - k_2^2}{k_2^2} \quad (8)$$

And if β equals one, then θ_e may be defined as the band edge desired and:

$$k_2^2 = \frac{1}{1 + \sin \theta_e} \quad (9)$$

Thus the coupling coefficient of the auxiliary network k_2 may be expressed solely in terms of the band edge desired.

Coupling coefficient k_1 may then be expressed in terms of the midband coupling and the band edge θ_e desired:

$$k_1^2 = \frac{1}{1 + K \left(\frac{\sin \theta_e}{1 + \sin \theta_e} \right)^2} \quad (10)$$

yielding the complete design criteria for the invention.

The coupling factors k_1 and k_2 may be calculated from the even and odd mode impedances of the coupled lines:

$$k = \frac{Z_{oe}/Z_{oo} - 1}{Z_{oe}/Z_{oo} + 1} \quad (11)$$

where the even-mode impedance Z_{oe} is the characteristic impedance of a single coupled line to ground when equal currents are flowing in two coupled lines and the odd-mode impedance Z_{oo} is the characteristic impedance of a single line to ground when equal and opposite currents are flowing in two coupled lines.

If it is desired that the coupler be matched to a terminating transmission line of characteristic impedance, Z_o , it is necessary that:

$$Z_o = \sqrt{Z_{oe} Z_{oo}} \quad (12)$$

In a specific embodiment of the invention a 10 db. coupler with type N terminals was constructed. The directional coupler had a frequency range of 1 to 4 GHz with a variation in

coupling of ± 0.35 db. The SWR was a maximum of 1.25 and the directivity was 20 db. minimum.

An important feature of the invention is the small physical size achieved by placing the compensating network in the coupled output branch. Another important feature of the invention is the less exacting construction tolerances thereby achieved.

Another important feature of the invention is the virtual independence of the characteristics of the compensating network from the coupling value.

Another important feature of the invention is that the compensating network is determined solely from the bandwidth desired.

Another important feature of the invention is the adaptability of the structure to accommodating terminals at different locations. FIG. 1 shows the output terminals being on the opposite points of a longitudinal axis of the directional coupler. But the invention operates well with the output terminals in space quadrature at other suitable angles. Also, the coupled output port is shown orthogonal to the longitudinal axis of the directional coupler. But the invention operates well with the coupled output port at virtually any suitable angle.

Another important feature of the invention is the adaptability of the directional coupler to operation in a variety of frequency ranges. The center frequency of the invention may be determined by the electrical lengths of the coupled end auxiliary compensating sections. As stated above, the bandwidth of the invention depends solely upon the coupling coefficient of the auxiliary compensating networks.

The invention may be constructed of parallel plate transmission line, microstrip or any other TEM waveguide configuration. The auxiliary compensating networks network, be integrally combined with a single or multiple section coupler to form a flat broadband directional coupler. But the invention works well with auxiliary compensating networks constructed in a separate package and then connected to the coupled port of a separate single or multiple section coupler whose coupling coefficient has been chosen as above.

Another important feature of the invention is the adaptability of the flat directional coupler to utilization of different types of connectors. The connectors may be any type of coaxial connectors, axial leads, or virtually any type to insure proper mating.

Another important feature of the invention is the low ripple and high bandwidth which may be achieved by compensating multiple section couplers with multiple or single section auxiliary compensating networks. Moreover, single section couplers may be compensated by a multiplicity of single or multiple section auxiliary compensating network to provide reduced ripple and improved bandwidth. Thus, extremely broadband, low ripple couplers may be constructed in a compact efficient package.

Other modifications and uses of and departures from the specific embodiments described herein may be practiced by those skilled in the art without departing from the inventive concepts. Consequently, the invention is to be construed as embracing each and every novel feature and novel combination of features present in or possessed by the apparatus and techniques herein disclosed and are limited solely by the spirit and scope of the appended claims.

What I claim is:

1. A coupled line compensating network for use with a TEM mode first transmission line coupler operative over a frequency range embracing a predetermined center frequency, said first coupler including means defining input, main output and coupler output ports and means defining main and coupled branches, said main branch being arranged for carrying an electrical signal, said coupled branch being arranged for carrying a coupled signal in response to the signal carried by said main branch, said coupled line compensating network including means defining a series conductor having two ends for connec-

tion by one of said ends to said coupler output port for carrying said coupled signal to said other end, means defining at least one auxiliary branch coacting with said series branch for establishing a coupling coefficient therebetween k_2 and substantially isolated from said main branch for rendering the ratio of said coupled signal to said signal on said main branch substantially insensitive to frequency variation, said coefficient k_2 being defined by the following equation:

$$k_2^2 = \frac{1}{1+K \frac{\sin \theta_e}{1+\sin \theta_e}}$$

wherein θ_e defines the band edge of said frequency range.

2. A compensating network according to claim 1 and further comprising, said first coupler, and means connecting said first coupler to said series branch to provide a compensated flat directional coupler, said first coupler comprising coupled lines characterized by a coupling coefficient k_1 defined by:

$$k_1^2 = \frac{1}{1+K \frac{\sin \theta_e}{1+\sin \theta_e}}$$

wherein K is the midband coupling of a compensated flat directional coupler comprising said first coupler and said compensating network.

3. A compensated flat directional coupler according to claim 2 including at least two of said auxiliary branches coacting with said series branch each for a length corresponding substantially to an odd multiple of quarter wavelengths at said

5 15 20 25 30 35 40 45 50 55 60 65 70 75

center frequency of said first coupler.

4. A compensated flat directional coupler according to claim 3 comprising two of said auxiliary branches coacting with said series branch and coupled thereto each for a length corresponding substantially to one quarter wavelength at said center frequency.

5. A compensated flat directional coupler according to claim 4 wherein said first coupler comprises a single section coupled transmission line coupler.

10 6. A compensated flat directional coupler according to claim 2 wherein said first coupler includes means defining a multiple section transmission line coupler and at least two of said auxiliary branches coact with said series branch to define multiple section transmission line couplers.

7. A compensated flat directional coupler according to claim 3 wherein said first coupler comprises a single section coupled transmission line coupler and said auxiliary branches coact with said series branch to define multiple section transmission line couplers.

8. A compensated flat directional according to claim 3 wherein the coupling coefficient achieved by each of said auxiliary branches coacting with said series branch are substantially equal to one another.

20 25 30 35 40 45 50 55 60 65 70 75

9. A compensated flat directional coupler according to claim 3 comprising an even number of said auxiliary branches coacting with said series branch each for a length corresponding substantially to an odd multiple of quarter wavelengths at said center frequency of said first coupler.
